UNITED STATES PATENT OFFICE

JOHN O. MORGAN, OF HIGH POINT, NORTH CAROLINA

COIN OR CHECK CONTROL DEVICE

Application filed May 16, 1931. Serial No. 537,929.

This invention relates to certain new and useful improvements in coin or check control devices and the primary object of this invention is to provide a device of the character above mentioned, especially but not essentially adapted for controlling the valve of a water meter.

A still further object of the invention is to provide a device of the character above mentioned, which will control the amount of water to pass through the meter by reason of means suitably connected with the valve of the meter for retaining the valve open for a predetermined period of time.

The present application is an improvement on a coin control device shown and described in my copending application Serial No. 456,581 filed under date of May 28, 1930.

Many objects and advantages of the present invention, together with its nature will be best understood from a study of the following description, taken in connection with the accompanying drawings wherein:

Figure 1 is an elevational view of one side of the device.

Figure 2 is a similar view of the opposite side of the device.

Figure 3 is a top plan view thereof.

Figure 4 is a sectional elevational view taken substantially on the line 4-4 of Figure 1.

Figure 5 is an end elevational view of a coin or check receiving housing.

Figure 6 is a side elevational view of a shiftable plate to be hereinafter more fully referred to.

Figure 7 is a top plan view of a shifting lever the roller mounted thereon being shown in longitudinal section.

Figure 8 is a plan view of a second coin shifting plate.

With reference more in detail to the drawings, it will be seen that in the preferred embodiment of the invention, there is employed a casing, suggested by broken lines in Figure 1 and including among other parts a bottom plate C that is adapted to be bolted either to the water meter (not shown) or to a suitable support in operative relation to the meter and in proximity thereto. Extending through the plate C is a crank arm 17, the

lower outer end of which is suitably connected to the crank arm of the meter valve (not shown). The crank arm 17 is normally urged in one direction for retaining the meter valve closed, through the medium of a rod 19 that has a forked end pivoted to the crank arm 17 as at 17a.

The free end of the rod is slidable through an apertured guide lug 20 provided on the under face of the casing plate or bottom C, and a spring 18 is convoluted about the rod 19 between the forked end of the rod and the lug 20, for normally urging the rod 19 toward the right in Figure 1.

To the inner end of the crank arm 17 there is pivotally connected one end of a coin shifting lever 21. Adjacent its free end, the lever 21 is provided with an elongated slot 22 through which passes a horizontal shaft 25 journaled in the casing between uprights 40 rising from the bottom C. Mounted on the shaft 25 and at opposite sides of the lever 21 are spacer washers 24.

On the free end of the lever 21 and laterally disposed is a roller 23 normally retained inwardly of a radial slot 27 provided on a disk 26 keyed to the shaft 25 adjacent the lever 21. A guide sleeve 28 is suitably fixed to one side of the disk 26 and slidably arranged within the sleeve is a shiftable plate 29 that at one end is provided with a convex edge normally engaging the periphery of the roller 23. As shown in Figure 8, the plate 29 is provided with an elongated longitudinal slot for accommodating the shaft 25.

Arranged within the casing rearwardly of and substantially in alignment with the disk 26 is a vertically disposed coin housing 30 that at its lower edge is bolted or otherwise secured to the plate or bottom member C. The coin receiving housing 30 at that end adjacent the disk 26 is open, and arranged within the lower portion of the housing and extending longitudinally thereof is a coin guide strip 30b. Slidable on the guide strip 30b is a coin shifting plate 31 that at its forward edge is provided with an arcuate notch 31a arranged in confronting relation to the arcuately notched end edge 29a of the plate 29.

The housing 30 on one side thereof is provided with a slot S through which extends a pin 31c projecting laterally from the shifting plate 31. Pivotally engaged with the outer end of the pin 31c is one end of a link 32 that is also pivotally connected with the free end of a crank arm 33 provided on a transverse shaft 34 journalled in opposed bearing blocks 47 mounted on the bottom or plate member C.

For rocking the shaft 34 there is provided a handle lever 35 suitably keyed to the shaft 34 at one end of the lever, the free end of the lever extending through an adjacent end of the casing, and being operable in a suitable slot in the casing.

From what has been hereinbefore stated, it will be apparent, that a coin is first inserted through the coin slot 30a provided in the upper portion of the housing 30 and the coin will be received on the guide strip 30b in line with the shifting plate 31. Handle 35 is rocked upwardly thus imparting swinging movement to the arm 33 which through the medium of the link 32 causes plate 31 to move toward plate 29 or in a direction toward the left in Figure 1.

The coin will of course be moved in a corresponding direction by the shifting plate 31 and when the edge of the coin engages the concave edge 29a of plate 29, plate 29 will then be moved toward the left in Figure 1. Plate 29 then acting on the roller 23 will cause lever 21 to move in a corresponding direction thus rocking the crank arm 17 against the action of spring 18 whereby the valve of the meter will be moved to an open position.

The movement of plate 29 toward the left in Figure 1 is continued until the convex edge of the plate is beyond the periphery of the disk 26 for engaging roller 23 with the periphery of the disk, and the roller will remain in engagement with the periphery of the disk 26 until the disk 26 has completed one full complete revolution.

Suitable means for transmitting power to the disk 26 for rotating the same upon initial opening of the valve is provided, and is herein shown somewhat in detail, and also so shown in my referred to application.

The driving means just referred to includes a shaft 51 forming part of the mechanism of the meter, and provided with a worm 41 in mesh with a worm wheel 42 on a horizontal shaft 45 journalled in bearings 46 and extending transversely to the shaft 25. Shaft 45 is also provided with a worm 44 in mesh with a worm wheel 43 on shaft 25. Thus it will be seen that rotative movement of shaft 51 is transmitted to shaft 25 for driving the disk 26.

Suitable means is provided for locking the shifting plate 31 at the limit of its forward movement, that is at the limit of its move-

ment toward the left in Figure 1. Such means consists of a longitudinally curved locking lever 38 pivoted intermediate its ends on a bracket B projecting laterally from one side of the coin housing 30. At its forward end the lever 38 is provided with a laterally inwardly directed lug 38a adapted to be passed through an opening in an adjacent side of the housing 30 to engage an opening or aperture 31b in the plate 31, when the plate 31 is in said last referred to position. The lever 38 is swung about its pivot to a locking position during the shifting of the lever 21 toward the left in Figure 1 through the medium of a spring 37 and engaged with that end of the lever equipped with the lug 38a, which spring 37 is mounted on a vertical arm 36 secured to the lever 21 at the pivoted end of the lever 21.

When the disk 26 has completed its full revolution, it will be apparent that the valve of the meter controlled by the crank arm 17 will be moved to a closed position, due to the fact that the roller 23 will then enter the notch 27 and be moved inwardly of the notch and spring 18 will then be free to act on the rod 19 for urging the crank 17 toward its position in Figure 1 thus retracting the lever 21. During the retraction of the lever 21, spring 27 will then engage that end of the locking lever 38 remote from the lug 38a releasing the lever 38, that is causing the lever to swing to its full line position shown in Figure 3.

Handle lever 35 then by its own weight or by proper manipulation will return to its full line position shown in Figure 1 which, through the medium of shaft 34, arm 33 and link 32 will cause the plate 31 to move to its dotted line position shown in Figure 1 so that the parts are all now in their normal position, plate 29 having been moved to its normal position through the medium of roller 23 engaging the plate during retraction of the lever 21.

For the coins or checks, discharged into the casing from the housing 30, there is provided a suitable pan 47 arranged adjacent one end of the casing.

It is thought that from the foregoing description, taken in connection with the accompanying drawings a clear understanding of the operation, structure, utility and advantages of devices of this character will be had by those skilled in the art without a more detailed description thereof.

It is also to be understood, although I have referred to the use of this device in conjunction with the valve of a water meter, that the device can be readily adapted to other such forms of mechanism as will admit of a coin or check control device being associated therewith.

Having thus described my invention, what I claim as new is:

1. A coin or check control device comprising in combination a rotatably mounted disk, 5 a shiftably mounted member constrained to move radially with respect to the disk, said disk provided with an inwardly directed radial notch, and means disposed laterally on said shiftable member normally engaged 10 with said notch for retaining the disk against rotation, and engageable with the periphery of the disk when said shiftable member is moved relative to the disk in one direction, whereby to retain said shiftable member in 15 its shifted position during the completion of one revolution of the disk, and means for shifting said shiftable member, said last mentioned means comprising a pair of aligned plates constrained to move radially with respect to the disk, said plates adapted to accommodate between adjacent ends thereof a coin or check, one of said plates normally engaging said lateral member and manual 20 means engageable with the other of said plates for shifting the latter whereby said plates and said coin or check are moved simultaneously in one direction for effecting a movement of said lateral member outwardly of the notch for engagement with the periphery of said disk.
2. A coin or check control device comprising in combination a rotatably mounted disk, a shiftably mounted member constrained to move radially with respect to the disk, said disk provided with an inwardly directed radial notch, and means disposed laterally on said shiftable member normally engaged with said notch for retaining the disk against rotation, and engageable with the periphery of the disk when said shiftable member is moved relative to the disk in one direction, whereby to retain said shiftable member in 35 its shifted position during the completion of one revolution of the disk, and means for shifting said movable member, said last mentioned means comprising a pair of aligned plates constrained to move radially with respect to the disk, said plates adapted to accommodate between adjacent ends thereof a coin or check, one of said plates normally engaging said lateral member and manual 40 means engageable with the other of said plates for shifting the latter whereby said plates and said coin or check are moved simultaneously in one direction for effecting a movement of said lateral member outwardly of the notch for engagement with the periphery of said disk, means operable upon 45 shifting movement of said plates in said one direction for locking said other plate in its shifted position, said means being operable upon the return of said movable member to release said other plate whereby said other plate is free to move to its normal position

upon entrance of said lateral member into said notch.

3. In a coin control apparatus, in combination, a shaft, a disk mounted thereon for rotation with the shaft, and having a radial notch, means for rotating said shaft and including a pivoted member, a shiftable member connected with said pivoted member and being also provided with a roller normally engaged in said notch, a second shiftable member and engageable with said roller for moving the latter out of the notch and into peripheral engagement with said disk, coin controlled means for shifting said second shiftable member, yieldable means acting on said pivoted member to normally retain said roller within said notch, and operable to return said shiftable member and said pivoted member to their normal positions subsequent to a complete revolution of said disk.

4. In a coin control apparatus, in combination, a rotatably mounted disk, a pivoted member, means controlled by said pivoted member for rotating said disk upon swinging movement of the pivoted member in one direction, a shiftable member connected with the pivoted member and provided with a roller for locking the disk and arranged for peripheral engagement with the disk upon swinging movement of the pivoted member in said one direction, a second shiftable member movable radially relative to the disk and engageable with the roller for moving the latter into peripheral engagement with the disk, coin controlled means for shifting said second shiftable member, and said roller being arranged to subsequently engage said second shiftable member upon completion of a full revolution of said disk to thereby return said second shiftable member simultaneously with the retraction of the first-named shiftable member.

In testimony whereof I affix my signature.

JOHN O. MORGAN.
